CIRCUIT TESTING APPARATUS
Earl L. Clemens, Saginaw, Mich., assignor of one-half to Mildred Clemens, Saginaw, Mich.

Application December 20, 1944, Serial No. 569,023

Priority claimed. 1 Claim. (Cl. 175-183)

This invention relates to circuit testers for testing or examining the wiring of electrical apparatus for continuity or for grounding, for identifying individual conductor in cables and installations including a plurality of conductors and for like purposes.

Its main object is to provide a simple compact and efficient testing apparatus of very small size and weight which may be used even where conditions are such that on account of noise a buzzer indication is unreliable.

The invention is described in the following specification and is illustrated in the accompanying drawings by way of example, it being understood that the modification of the invention shown is illustrative and that further modifications in this case may be easily constructed by the experts skilled in the art by following the general idea laid down in the specification describing the modification shown.

In the accompanying drawings:

Figure 1 is a top view of the testing apparatus showing the container or box when opened.

Figure 2 is an elevational and partly sectional view of the lid or cover.

Figure 3 is a view of the circuit tester box when in a closed condition.

Figure 4 is a diagram of the circuit connection of the tester.

The instrument consists of a box with a lower container section 1 to which an upper lid or cover 2 is hinged. This lid section has the shape of a tray and is provided with side walls 4; it thus forms a container housing all the components used with the exception of the dry cells 5 which are accommodated in the lower container section 1. The hinges 3 are arranged at the lower end of the side walls 4 so that when the lid is turned around the hinges all the components housed in the lid and in the container are exposed and are accessible.

The lid section 2 houses a buzzer 6 and a lamp 7, consisting of a light bulb which is arranged in a shallow depression 8 of the lid 2. This depression is provided with an opening or hole 9 surrounded with an upturned flange 10. Below the said depression 8 the lamp base 11 is fixed on small pieces of sheet metal 15 spot welded to the sides of lid section 2 on said base the bulb of the lamp 7 is mounted in the usual manner, the connections being established by means of the binding posts 12, 13.

The light bulb 7 projects through the opening 9 in the depression 8 of the top wall of the lid sec-

tion 2 and is protected by a sheet metal lid 16 which is spot welded to the top wall of the lid section 2.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

The lid section 2 is provided with a shallow depression 17 which is surrounded with an upturned flange 18.

operated with full battery voltage if the wire is a continuous one.

What I claim is:

A circuit testing arrangement comprising a container, consisting of two hinged hollow sections, the lower section being provided with a hole and adapted to house the cells of a dry cell battery, the upper hollow lid section carrying the testing equipment on its top wall, said equipment including a buzzer, a buzzer support plate for the same and a shield covering said buzzer and further including a lamp socket mounted adjacent to said buzzer support, said top wall being provided with a hole near the lamp socket for accommodating a signal lamp, mounted on the lamp socket, a transparent dome shaped cover over said hole, connecting posts on said buzzer and lamp socket, testing cables passing through the hole in the lower container section to the outside, one of said cables being connected with the battery and the other with one of the aforesaid connecting posts, and further flexible cables adapted to be accommodated within the space enclosed by the upper lid

section, said cables establishing a flexible connection between the battery, and one of the connecting posts and a parallel connection between said buzzer and said signal lamp.

EARL L. CLEMENS.
